D. F. BAUMGARTNER,
TILE PERFORATING MECHANISM.

FILED MAR. 25, 1922.

2 SHEETS—SHEET 2.

UNITED STATES PATENT OFFICE.

DANIEL F. BAUMGARTNER, OF CHATFIELD, OHIO.

TITLE-PERFORATING MECHANISM.

Application filed March 25, 1922. Serial No. 546,778.

To all whom it may concern:

Be it known that I, DANIEL F. BAUMGARTNER, a citizen of the United States, residing at Chatfield, in the county of Crawford 5 and State of Ohio, have invented certain new and useful Improvements in Tile-Perforating Mechanisms, of which the following is a specification, reference being had to the accompanying drawings.

10 This invention relates to certain improvements in tile perforating mechanisms and has relation more particularly to a device of this general character especially designed and adapted for use in connection with 15 drain tile, and it is an object of the invention to provide a novel and improved mechanism positioned and operating in a manner to perforate the tile as the same is discharged from the forming mold.

20 Another object of the invention is to provide a mechanism of this general character comprising a rotatable element provided with a plurality of circumferentially spaced perforating members supported for swinging movement, together with means for holding each of said members against swinging movement during the period the same is having working coaction with the tile.

25 The invention consists in the details of construction and in the combination and arrangement of the several parts of my improved tile perforating mechanism whereby certain important advantages are attained 30 and the device rendered simpler, less expensive and otherwise more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein:

45 Figure 1 is a view in side elevation showing perforating mechanism constructed in accordance with an embodiment of my invention and in applied position;

Figure 2 is an enlarged view, partly in 50 section and partly in elevation, of my improved mechanism as herein disclosed; and

Figure 3 is a view partly in end elevation of a structure as illustrated in Figure 2.

As disclosed in the accompanying drawings, F denotes a frame which supports the 55 conveyor C for carrying the tile after the

same has been discharged from the forming die D. W denotes a wheel supported by the frame F above the conveyor and in proper position to cut the tile into desired 60 lengths. The foregoing forms no part of my present invention and a detailed description and illustration thereof are believed to be unnecessary.

Extending upwardly from each side of 65 the frame F and at a desired point in advance of the wheel W or at a point between the wheel W and the forming die D is a standard or upright 1 provided at its upper portion with a bearing 2 for an end portion 70 of the shaft 3. Said shaft 3 is disposed transversely of the frame F or more particularly the conveyor C and has fixed thereto, in desired spaced relation, the wheels 4. The wheels 4 are of the same radii and pref- 75 erably twelve inches in diameter and spaced apart about two and three-quarter inches.

Positioned between the peripheral portions of the wheels 4 and supported thereby for rotary movement are the shafts 5. Underlying each of the shafts 5 with its central portion fixed thereto is a plate 6 substantially rectangular in plan. Depending from the plate 6 at the longitudinal center thereof and adjacent the opposite ends 80 thereof are the series of transversely disposed depending perforating members or pins 7. The plate 6 maintains by gravity a substantially horizontal position during the complete rotation of the wheels 4. 85

Each of the shafts 5 is so located that as a plate approaches a tile T traveling with the conveyor C, the penetrating members or pins 7 will pierce the wall of said tile and thus produce the desired perforations. 90 As the peripheral speed of the wheels 4 is substantially the same as the speed of travel of the conveyor C and the tile T thereon, it will be readily understood that the pins or members 7 will penetrate the wall of the 100 tile with substantially a direct thrust and be similarly withdrawn so that the desired perforations will be produced without distortion.

It is of importance that each of the shafts 105 5 and the plate 6 carried thereby be held against swinging or rocking movement. In order to prevent such rocking or swinging movement, each of the shafts 5 extends outwardly of one of the wheels 4 and terminates 110 in an upwardly disposed arm 8 provided with an outstanding lug or extension 9,

This lug or extension 9 engages within an arcuate trackway 10 positioned in close proximity to the lower portion of the adjacent wheel W, the curvature of such trackway being such to positively assure the plate 6 being maintained in substantially a horizontal position and the depending pins or members 7 substantially vertical during the time said members or pins are penetrating the wall of the tile T and being withdrawn or retracted. The trackway 10 is herein disclosed as substantially U-shaped in cross section with its open face opposed to the adjacent wheel W and the entrance 10 end of said trackway 10 is enlarged, as at 10^a, to facilitate the entry of the lug or extension 9 into said trackway.

While the engagement of the members or pins 7 with the wall of the tile T will effect the desired rotation of the wheels 4, I find it of advantage to place the shaft 5 in driven connection with the cutting wheel W.

The trackway 10 may be maintained in applied position in any desired manner but, as herein disclosed, said trackway is supported by the arms 11 interposed between and connected to the end portions of the trackway 10 and the upper portion of the adjacent standard or upright 1.

From the foregoing description it is thought to be obvious that a tile perforating mechanism constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A perforating mechanism comprising a member supported for rotary movement, plates, means for connecting said plates to the member for rocking movement, penetrating members depending from the plates, and means for holding said first named mem-

ber against rotation during the period the penetrating members are in engagement with the work.

2. A perforating mechanism comprising a member supported for rotary movement, plates, means for connecting said plates to the member for rocking movement, penetrating members depending from the plates, an arm extending from the first named member, and a trackway with which said arm engages to hold the member against rotary movement during the period the penetrating members are engaged with the work.

3. In combination with a forming die for a tile and a conveyor upon which the tile is discharged from the die, a rotatable member positioned above the conveyor, a plate supported by said member, and a penetrating member depending from the plate for swinging movement, said penetrating member piercing a wall of the tile carried by the conveyor upon rotation of said rotatable member.

4. In combination with a forming die for a tile and a conveyor upon which the tile is discharged from the die, a rotatable member positioned above the conveyor, a plate supported by said member, a penetrating member depending from the plate for swinging movement, said penetrating member piercing a wall of the tile carried by the conveyor upon rotation of said rotatable member, and means for holding the plate against swinging movement during the period the penetrating member is engaged with the tile.

5. In combination with a forming die for a tile and a conveyor upon which the tile is discharged from the die, a rotatable member positioned above the conveyor, a plate supported by said member, a penetrating member depending from the plate for swinging movement, said penetrating member piercing a wall of the tile carried by the conveyor upon rotation of said rotatable member, and means independent of the travel of the tile for rotating said rotatable member.

In testimony whereof I hereunto affix my signature.

DANIEL F. BAUMGARTNER.
